BICYCLE SEAT

Frank P. Brilando, Niles, Ill., assignor to Arnold, Schwinn & Co., Chicago, Ill., a corporation of Illinois

Filed Jan. 15, 1965, Ser. No. 83,469

Term of patent 14 years

(Cl. D90—16)

FIG. 1 is a side elevational view of a bicycle seat showing my new design, the broken line portions of a bicycle being included for illustrative purposes only;

FIG. 2 is a fragmentary enlarged top plan view thereof; FIG. 3 is a fragmentary elevational view of the side opposite that shown in FIG. 1;

FIG. 4 is a fragmentary rear elevational view thereof; FIG. 5 is a fragmentary front elevational view thereof;

FIG. 6 is a side elevational view of a modified form of the bicycle seat shown in FIG. 1.

I claim:

The ornamental design for a bicycle seat, as shown and described.
